UNITED STATES PATENT OFFICE.

AUGUST M. GIMPEL AND PETER YEAGER, OF ST. LOUIS, MISSOURI.

HUB-LINER.

1,146,790.

Specification of Letters Patent. Patented July 20, 1915.

Application filed January 12, 1915. Serial No. 1,825.

To all whom it may concern:

Be it known that we, AUGUST M. GIMPEL and PETER YEAGER, citizens of the United States, residing at St. Louis, in the 5 State of Missouri, have invented certain new and useful Improvements in Hub-Liners; and we do hereby declare the following to be a full, clear, and exact description of the invention, such as will enable 10 others skilled in the art to which it appertains to make and use the same.

This invention relates to a hub liner and is particularly adapted for use on engine truck bearing boxes.

15 An object of the invention resides in the provision of a device which may be readily attached to a bearing box of a type used at the present time.

A further object of the invention resides 20 in the provision of a bearing portion on the liner against which the hub of the wheel will bear and thus the lateral play of the axle will be done away with.

With these and other objects in view, such 25 as will appear as the description progresses, our invention comprises the combination and arrangement of parts as set forth in and falling within the scope of the appended claims.

30 Referring to the drawings: Figure 1 is an end elevation of our device, showing the same in place on a bearing box. Fig. 2 is a similar view showing a portion of the bearing member of the liner broken away to 35 illustrate the manner in which the bearing member is secured to the liner. Fig. 3 is a perspective view, showing the top and side retaining flanges. Fig. 4 is a fragmental view, showing a modification of the means 40 for retaining the liner on the bearing box.

Referring to the drawing wherein like parts are indicated by like characters throughout the several views: The bearing box is indicated by the reference character 1 45 in which is located an axle supporting member 2 made preferably of brass. In order that the lateral play of the wheels may be taken up, we have provided a liner which consists of a metallic plate 3 mounted on 50 one end of the bearing box and being of inverted U-form to conform to the contour of the said end of the bearing box. This liner is maintained upon the bearing box from downward and lateral movement by flanges 55 4 and 5, respectively. In the flanges 5 a

plurality of holes are provided through which extend tap bolts 6, which prevent the upward movement of the liner. Secured to the outward face of the liner is a bearing member 7, made preferably of Babbitt 60 metal, against which the hub of the wheels bear. In order that this member may be secured to the face of the liner without the necessity of passing screws or bolts therethrough and in order that it may be positively secured thereto, we have provided 65 the liner with a plurality of holes 8 which extend completely through the plate 3 and are counter-sunk on the inner face of the said plate.

In forming the bearing member 7 the face of the plate 3 is tinned, the metal is poured on the outer face of the plate 3, the plate 3 being set in a mold, and the poured metal flows into the holes 8 in the plate 3 so as to 70 form cleats 9 integral with the bearing member 7 and having flanges on their inner ends which are located in the counter-sunk portions of the holes 8 so that the said 75 bearing member will be prevented from displacement when in use.

In assembling the device the plate 3 is passed down over the end of the bearing box until the upper flange 4 engages the top of the bearing box at which time the bolts 6 are passed through the flanges 5 and thus 80 the liner will be prevented from displacement from the box.

We contemplate the modification of the manner of securing our device to the bearing box and to this end we omit the tap bolts 6 and in lieu thereof provide extensions 10 on the lower end of the plate 3 which after the liner has been placed on the bearing box are bent upwardly and engage the end faces of the sides of the bearing box and thus the liner is prevented from lateral movement by the flanges 5, from vertical upward movement by the extensions 10 and from downward movement by the flange 4 and from being entirely displaced from the end of the box by the hub of the wheel.

From the foregoing description it will be seen that we have provided a device which 105 may be secured to a present day type of axle bearing box used on a locomotive, and we have so constructed the device that a bearing member is provided thereon against which the wheel of the locomotive may 110

bear, which bearing member is secured to the supporting plate in such manner that irrespective of the wear thereon a smooth surface will always be provided.

5 While we have illustrated and described a particular embodiment of our invention, we have merely done so for the sake of convenience and we do not wish to be limited to that particular embodiment as it is obvious 10 that numerous changes may be made in the details of construction thereof without in any way departing from the spirit of the invention or exceeding the scope of the appended claims.

15 What we claim is:—

1. The combination with a bearing box, of a wheel hub liner secured to one end thereof, the said liner comprising a supporting plate and a bearing member cast 20 thereon.

2. The combination with a bearing box, of a wheel hub liner secured thereto, the said liner consisting of an inverted U-

shaped plate having a plurality of holes 25 therein countersunk from one side of the plate, and a bearing member cast on said plate and having portions extending through said holes, the ends of said portions being enlarged to fit into the countersunk portions of the holes.

3. The combination with a bearing box, of a wheel hub liner detachably secured thereto, the said liner being of inverted U-shape and having flanges thereon to engage the top and sides of the bearing box, the 35 said liner having further, a flat metallic bearing member cast on the outer face thereof.

In testimony whereof, we affix our signatures in the presence of two witnesses.

AUGUST M. GIMPEL.
PETER YEAGER.
